COMPOSITE SHIP CONSTRUCTION

Filed July 1, 1944

UNITED STATES PATENT OFFICE

2,473,039

COMPOSITE SHIP CONSTRUCTION

Rolland C. Sabins, Seattle, Wash.

Application July 1, 1944, Serial No. 543,106

18 Claims. (Cl. 114—65)

1

My invention relates to vessel construction, and more particularly to the prefabricated construction of fore and aft parts of smaller boats.

Except perhaps for boats of a length less than about twenty feet it has been the practice heretofore for boats to be custom built. Even when several boats have been constructed in accordance with a common plan, the number of such boats required has usually been insufficient to warrant the employment of mass production technique.

It is a principal object of my invention to make certain of the more complicated parts of boats available on a mass production basis, which parts are suitable for incorporation in boats of the same general type, although they may vary somewhat in size and shape.

In hull construction the most difficult portions to fabricate have been those which have surfaces of compound curvature between the keel and the gunwale. This is particularly true of the stern portion of the ship, and to a lesser extent of the bow. Between these portions the sides of a tug boat or fishing boat, for example, of forty to one hundred feet in length, are of single convex curvature. At the stern, however, the upper portion of the side is of convex external curvature, while the lower portion is concave. At the bow, on the contrary, the upper portions of the sides frequently are somewhat concave, while the lower portions are convex.

It is therefore more particularly an object of my invention to provide prefabricated stern and bow portions intended especially for incorporation in boats of medium size, such as forty to one hundred feet in length, although the same principles may be employed for smaller or larger vessels.

It is a further object of my invention to make such prefabricated sections of rugged construction, and to arrange such sections for convenient and secure attachment to elements of the intermediate boat structure conventionally employed.

Another object is to utilize the space within such prefabricated sections for cargo space, and more particularly to form them as tanks for holding liquid, whether oil for cargo or fuel, or water for ballast or for use aboard ship.

Still an additional object is to incorporate in the prefabricated stern section mounting fixtures which usually require considerable labor and skill to install, such as upper and lower bearing blocks for the rudder post, and the tubular housing for the propeller shaft.

Other advantages of my invention will be

2

pointed out in connection with the following description of the construction which I now prefer.

Figure 1 is a side elevation view of a representative type of boat incorporating prefabricated bow and stern sections according to my invention.

Figure 2 is an athwartships sectional view through the stern prefabricated section taken along line 2—2 of Figure 1.

10. Figure 3 is an athwartships sectional view through the bow prefabricated section on line 3—3 of Figure 1.

15. Figure 4 is a fragmentary horizontal sectional view at line 4—4 of Figure 1, illustrating the interconnection of the stern prefabricated section with the midship section, which latter section may be of conventional boat structure, intermediate the bow and stern prefabricated sections.

20. Figure 5 is a fragmentary detail sectional view on line 5—5 of Figure 1 showing the interconnection between the stem of the bow prefabricated section and the conventional stem post.

Boats of the size and type for which my structure is most useful are usually made of wood, including upright wooden frames or ribs secured together by a solid wall of planks running fore and aft. At the stern of the boat the frames were of compound curvature, having an upper portion of convex outer contour and a lower portion of concave outer contour. In attaching the planks to such frames it was necessary not only to bend them inward around the stern, but also to twist or warp their contour from the convex shape of the lower portion of the hull amidships to the concave shape at the stern. It was therefore difficult both to shape the frames to the desired compound curvature and to warp the planking. The same considerations apply in lesser degree to construction of the bow. Consequently the fabrication of these stern and bow portions from wood required much more labor and skill than other parts of the hull of comparable surface area.

45. My invention, therefore, contemplates the prefabrication of these complicated bow and stern sections as standard parts, which are connected together by an intermediate or midship section. For different boats such midship sections may be of different lengths or of different maximum beam, within limits, depending upon the length, capacity, and general design of boat required. This midship portion of the boat can be of conventional wood structure having substantially convex sides so that its construction will not be described in greater detail than necessary to in-

dicate the manner in which it is integrated with my prefabricated sections.

As shown in Figure 3, the upper portion of the bow is usually somewhat concave exteriorly, and consequently the frames or ribs 1 must be bent as shown. They need not be of compound curvature, however, because the lower portion of the bow is formed by the prefabricated bow section 2 of my invention. I prefer that this prefabricated bow section constitute a storage tank which, for example, may be used to hold drinking water or water for the ship's boilers. In any event, however, it will be hollow, and will have a top plate 20 and internal intersecting partitions, such as the central fore and aft baffle plate 21, and the athwartships baffle plate or plates 22. These baffle plates are welded or otherwise made integral with the top plate 20 and the sides of the section 2, but if the prefabricated section is to be used for a storage tank some or all of such plates should terminate above the bottom of the section, as shown in Figure 3, to afford intercommunication between the compartments. If it were desired to store different types of liquid in the bow section, however, one or more of the baffle plates could extend to the bottom of the section, and be welded to it, to form partitions separating the compartments.

It will be understood, of course, that the walls of the tank form the exterior of the bow section, and that no planking covers it. I prefer that this prefabricated section extend above the water line, as shown in Figure 1, and it will be made of fairly heavy steel plate, so that, particularly when stiffened by the partitions 21 and 22, it can withstand quite heavy impacts from floating logs, ice, or other objects which the boat may strike, without being injured. Even if the tank structure should be ruptured by such an impact the seaworthiness of the boat would not be greatly affected adversely, because the tank is sealed from communication with the rest of the hold, and consequently the only loss would be of liquid which might be stored in the tank section.

In order to withstand head-on impacts to even better advantage, the prefabricated section 2 has a solid stem strip or bar 23 of metal, which preferably extends from substantially the bottom of the keel or false keel 10 upwardly to the top of the planking. Above the tank portion of the prefabricated section this stem bar may be secured to the stem post 11 by bolts or equivalent securing members 24 extending into or completely through them. As usual, the sides of the stem post are rabbeted to receive the forward ends of the planks 12 flush with the front portion of such post, and such plank ends are secured to the post in conventional fashion.

To the bottom of the prefabricated tank section is welded or otherwise integrally secured the upper flange of a T-bar or I-beam member 25 having the lower edge of its web similarly secured to the stem bar 23. A flange plate 26 is likewise welded to the lower edge of the aft portion of such member's web, which is beveled upwardly and rearwardly so that such plate forms one element of a scarf joint between my prefabricated section and the keel or false keel 10. Bolts 27 extending through the complementally scarfed fore portion of the keel or false keel 10 and at least the lower flange plate 26 secure the aft portion of my prefabricated bow unit to the intermediate boat section of wood construction. Such bolts may also extend through the upper flange of member 25, if desired, as shown. After

the parts have thus been joined the channels between the upper flange of member 25, flange plate 26, and stem bar 23 may be filled with a suitable composition 28, such as concrete, as shown in Figure 3, so that the sides of this portion of the unit will be flush with the sides of the keel or false keel 10.

To complete the attachment of conventional frame members to my prefabricated bow section angle brackets or bars 29 may be welded, or secured in an equivalent manner, to the top plate 20 at locations spaced inwardly from the outer walls sufficiently to accommodate the frames 1 and planking 12. Before the planking is applied to the frames their lower ends will be bolted to these bars or brackets in the manner indicated in Figure 3. The forward ends of the planks below the top plate 20 of the unit 2 will be attached directly to the aft portion of the tank in a manner similar to the connection between the aft ends of such planks and the stern tank section, as illustrated in Figure 4 and as will be described in detail hereafter.

The stern prefabricated section 3 is larger and of considerably more complicated shape than the bow section described above. The sides of the stern section are of compound curvature, as shown in Figure 2, having an upper part of convex exterior shape and a lower part which is concave while portions of the central wooden hull midship section adjacent to the forward terminus of such stern section are of substantially simple convex curvature. Aside from such difference in shape, however, the structural elements and features correspond generally to the bow section. Thus the top of the stern section is closed by a plate 30, and it is stiffened interiorly by a central fore and aft partition 31 and one or more athwartships partitions 32, serving as baffle plates. While these partitions again have been shown spaced from the bottom of the section to afford intercommunication between the several compartments, if the unit is used as a storage tank in the manner intended, one or more of these partitions may extend to the bottom of the unit to divide it into separate compartments. This unit may be used to carry fuel oil for the boat's engines, if desired.

To accommodate the propeller shaft 13 a tube 31' may be carried by the lower edge of the fore and aft partition 31. This tube will be sealed to the fore and aft tank walls, so that the propeller shaft may extend completely through the tank without coming into contact with its contents. Moreover this tube, or the aft wall of the tank adjacent to it, affords a sufficiently rigid structure to support the propeller shaft bearing 14. A stuffing box for the propeller shaft may be provided ahead of the tank unit's forward wall, since water filling tube 31' is sealed from the interior of the unit. Alternatively the stuffing box may be behind the aft wall of the unit.

In order to support the rudder a bar 33, preferably of inverted T-section, extends aft from the bottom of the stern unit, and terminates in a bearing for the lower end of the rudder post 15. Additionally a bracket 34 is mounted upon the upper aft portion of the unit 3 to constitute an upper bearing for the rudder post. An upright tube may extend through the tank in continuation of this bracket 34 to accommodate the steering post extending upwardly above top plate 30.

To the bottom of the unit 3 is welded an element 35 of structural shape, preferably of I-beam section, extending a considerable distance ahead

of the forward wall of the unit. The fore portion of its web is cut on an upward and forward slope, and a flange plate 36 is welded to it to constitute one element of a scarf joint. The aft end of the keel or false keel 10 is complementally scarfed to fit against flange plate 36, and bolts 37 pass through the keel member 10 and at least flange plate 36, although they may continue through the upper flange of member 35, as shown, to complete the joint. The channel spaces at opposite sides of the I-beam web, and between the upper I-beam flange and flange plate 36, are then filled with concrete 38 or similar material, so that the sides of this structure also will be flush with the sides of the keel or false keel 10.

Above top plate 30 of the stern unit 3 horse-shoe frames 16 may be placed. The lowermost frame will be secured to the metal unit 3 by bolts 39 welded to the top plate 30 of such unit, and the superposed frames will then be held together in conventional fashion to form the stern bulwarks. It will be noted, however, that all these frames are above the bilge portion of the stern section, so that their exterior vertical curvature, if any, is slight.

The ends of the planks 12 adjacent to the forward end of stern unit 3 and the aft end of bow unit 2 are secured directly to these units in the manner shown in Figure 4. A bracket 4 is welded to the tank end wall, which in this instance is the forward wall of tank 3, although the arrangement would be the same if it were the aft wall of bow tank 2. These brackets are then bolted to the ends of bilge stringers 17 which are secured in the normal way to frames 1. In addition a bar 40 is secured to or formed as a flange integrally with the tank's end wall at a location spaced inward from the sides of the tank a distance equal to the thickness of the planking 12. Preferably this bar extends upward a substantial distance above the top of the prefabricated unit, and may project clear to the upper edge of the side to form one of the rib or frame members. The ends of the planks then overlap these flanges 40 alongside the tank, and the planks will be bolted directly to these bars along their entire length. The exterior of the planking will thus lie flush with the exterior of the tank sides. Calking material 41 may be wedged between the ends of the planks and the tank, as shown in Figure 4, in the same manner that the cracks between adjacent planks are calked.

The remainder of the boat construction is conventional, the deck 18, for example, being supported above the top plate of the bow and stern tank units by deck beams 19. If desired, however, one or both of these prefabricated bow and stern sections may extend to a height such that the deck is supported directly upon top plates 20 and 30, or they may even form part of the deck. Conversely, the heights of these sections may be less than illustrated in Figures 2 and 3, but preferably they are of approximately the height shown.

Similarly the bow and stern sections may extend farther aft or farther forward, respectively, than shown in Figure 1, but it is preferred that the fore and aft extent be at least as much as shown, so that they will extend over the portions of the hull which are most difficult to fabricate from wood, because of their compound curvatures.

It is not considered necessary to discuss in detail the operations adapted for prefabricating the units 2 and 3 since the technique employed would follow conventional metal tank and metal hull

manufacturing practice. Preferably the exterior plates would be bent to shape in jigs, and the various elements would then be welded together. Various methods of constructing such hollow tank structures of complicated shape are well known to people familiar with this field.

I claim as my invention:

1. A boat hull comprising a hollow metal stern hull bottom portion, a hollow metal bow hull bottom portion, a wooden hull portion between said stern hull portion and said bow hull portion, and further extending from stem to stern of the hull above said metal stern and bow hull bottom portions, and means securing said central wooden hull portion to said metal stern and bow hull portions so that the exterior surfaces of said metal hull portions and said central hull portion jointly form a smooth hull contour.
2. A boat hull comprising a hollow metal stern hull bottom portion having a metal structural member secured to its bottom and extending forward therefrom, a hollow metal bow hull bottom portion having a metal structural member secured to its bottom and extending aft therefrom, a keel member having its aft end rigidly secured to the forward projecting end of the metal structural member of said stern hull portion, and having its forward end rigidly secured to the aft projecting end of said bow hull portion structural member, a wooden hull portion between said stern hull portion and said bow hull portion, and means securing said central wooden hull portion to said metal stern and bow hull portions.
3. A boat hull comprising a hollow metal stern hull bottom portion having a metal structural member secured to its bottom and extending forward therefrom to form an end beveled rearwardly and downwardly, a hollow metal bow hull bottom portion having a metal structural member secured to its bottom and extending aft therefrom to form an end beveled forwardly and downwardly, a keel member having its aft end rigidly secured by an end scarf joint to the forward projecting beveled end of the metal structural member of said stern hull portion, and having its forward end rigidly secured by an end scarf joint to the aft projecting beveled end of said bow hull portion structural member, a wooden hull portion between said stern hull portion and said bow hull portion, and further extending from stem to stern of the hull above said metal stern and bow hull bottom portions, and means securing said central wooden hull portion to said metal stern and bow hull portions.
4. A hollow metal prefabricated unit of a shape exteriorly conforming to an exterior bottom portion of a boat hull, and a metal bar integral with said unit and extending upwardly a substantial distance thereabove, adapted to be secured at spaced locations along its length to a portion of a boat hull above such unit.
5. A hollow metal prefabricated unit having an exterior shape conforming to a portion of a boat hull and terminating at one end thereof in upright edges spaced apart transversely of the hull, and a metal member of structural shape secured to the bottom of such unit and having an end portion projecting lengthwise a substantial distance beyond said upright edges at one end of such unit, said end portion being adapted to be secured to a boat keel member.
6. A hollow metal prefabricated unit having an exterior shape conforming to a portion of a boat hull, and a metal member of structural shape

secured to the bottom of such unit and having an end portion projecting lengthwise beyond such unit, said end portion being beveled to be secured to a boat keel member by an end scarf joint.

7. A metal tank unit of a shape conforming to the bottom bow portion of a boat hull, and a metal stem bar integral with said unit and extending upwardly a substantial distance thereabove, adapted to be secured at spaced locations along its length to the stem portion of a boat hull above such unit.

8. A hollow metal unit of a shape exteriorly conforming to the stern bottom portion of a boat hull, a metal member of structural shape secured to the bottom of such unit and having its aft end projecting aft therebeyond, a rudder post journal element carried by the aft end of said structural member, and an upper rudder post supporting element secured to the rearward portion of such unit above said lower rudder post journal element.

9. A hollow metal unit of a shape exteriorly conforming to the stern bottom portion of a boat hull, a metal member of structural shape secured to the bottom of such unit and having its aft end projecting aft therebeyond, and a rudder post journal element carried by the aft end of said structural member, the forward end of said structural member projecting forward beyond such unit and being adapted to be secured to a boat keel member.

10. A metal tank unit for a boat having an exterior shape conforming to the shape of the stern bottom portion of a boat including upper convex and lower concave side portions exteriorly, and a tube extending fore and aft through the bottom portion of such unit for reception of a propeller shaft.

11. A metal tank unit for a boat having an exterior shape conforming to the shape of the stern bottom portion of a boat including upper convex and lower concave side portions exteriorly, a tube extending fore and aft through the bottom portion of such unit for reception of a propeller shaft, and an upright tube extending through the aft portion of the unit for reception of a rudder post.

12. A metal tank unit for a boat having an exterior shape conforming to the shape of the stern bottom portion of a boat including upper convex and lower concave side portions exteriorly, a tube extending fore and aft through the bottom portion of such unit for reception of a propeller shaft, an upright tube extending through the aft portion of the unit for reception of a rudder post, a metal member of structural shape secured to the bottom of such unit and having its aft end projecting aft therebeyond, a rudder post journal element carried by the aft end of said structural member, and an upper rudder post supporting element secured to the rearward portion of such unit above said lower rudder post journal element and in alignment with said upright tube.

13. A boat hull comprising a hollow metal hull

bottom portion extending from one end of the hull toward its center over only a portion of the length of the hull, a wooden hull top portion overlying the outer margin of said metal hull bottom portion, and means securing together said metal hull bottom portion and said wooden hull top portion in adjoining relationship to form a generally horizontal seam therebetween.

14. The boat hull defined in claim 13, in which the hollow metal hull bottom portion constitutes a liquid storage metal tank unit.

15. A boat hull comprising a hollow metal bow hull bottom portion having its outer marginal portion terminating slightly above the water line, a wooden hull top portion overlying the outer margin of said metal hull bottom portion, and means securing together said metal hull bottom portion and said wooden hull top portion in adjoining relationship to form a generally horizontal seam therebetween.

16. A boat hull comprising a hollow metal stern hull bottom portion, wooden curved stern bulwarks overlying the outer margin of said metal hull bottom portion, and means securing together the top of said metal hull portion and said wooden bulwarks in adjoining relationship to form a generally horizontal seam therebetween.

17. A boat hull comprising a hollow metal hull bottom portion, a wooden hull structure including a top portion, overlying the outer margin of said metal hull bottom portion, and a bottom portion, and means securing together said metal hull bottom portion and said wooden hull structure in adjoining relationship to form an upright seam between the wooden and metal hull bottom portions and a generally horizontal seam between the wooden hull top portion and the metal hull bottom portion.

18. A boat hull comprising a hollow metal stern hull bottom portion, a hollow metal bow hull bottom portion, a wooden hull structure including a top portion, overlying the outer margin of a least one of said metal hull bottom portions, and a bottom portion disposed between said metal stern hull bottom portion and said metal bow hull bottom portion, and means securing said bottom wooden hull portion to said metal stern and bow hull bottom portions.
